GRINDING APPARATUS MOUNTED ON AN
OVERHANGING SHAFTArthur C. Lind and Robert E. Klein, Milwaukee,
Wis., assignors to Chain Belt Company, Milwaukee, Wis., a corporation of Wisconsin

Application November 22, 1943, Serial No. 511,238

3 Claims. (Cl. 241—73)

1

This invention relates to a grinding device which because of its compact form and unique design may be employed in kitchens for grinding garbage such as vegetables, meats and small bones. Heretofore grinders have been built for home use and to aid in garbage disposal but such grinders have not been sufficiently rugged or lack the capacity to permit their use in commercial establishments such as hotels and restaurants. Grinders of the type used in industrial processing have not been satisfactory for this intermediate field either, because of their lack of efficiency, high initial cost and inability to stand up for a sufficient length of time when employed under such arduous service conditions.

To successfully meet the problem of grinding kitchen garbage in quantity, the machine must be capable of handling a great variety of materials. Fruit peelings, vegetable peelings, pieces of paper or cardboard, meat, bones, table scraps and even silverware or crockery are apt to be fed into the grinder, and while some of this material might be screened or sorted out, such procedure would be disagreeable and would delay quick disposal of the refuse.

It is an object of the present invention to provide a grinding machine in which there are means for protecting the operating parts from the excessive strains which would otherwise result should some foreign element such as silverware enter the grinding compartment.

A further object of the invention is to provide a grinder which without occupying very large space can nevertheless handle considerable quantity of material, one which will not be stalled easily and which will operate smoothly and with a very low power consumption.

More specifically, it is an object of this invention to provide grinding apparatus in which the grinding element is mounted on an overhanging shaft and in which the end of the shaft may have occasional bearing support in the event of certain conditions in grinding operations.

An additional object of the invention is to provide a garbage grinder in which the parts are so assembled and designed that the unit may be readily cleaned out, parts removed and grinding surfaces reground so as to extend the useful life of the machine.

These and other objects of the invention will be better understood after consideration of the following detailed description and the claims appended thereto taken in connection with the accompanying drawings.

In the drawings, Figure 1 is an elevation view,

2

partly in section, showing the end of the grinding device; Figure 2 is a section taken on the line 2—2 of Figure 1; Figure 3 is a perspective view of the rotor assembly removed from the housing; and Figure 4 is a perspective view of the hand crank used to turn the rotor when the motor is not in operation.

From an inspection of the drawings, it will be seen that the various elements making up the unit have been arranged in a compact form so as to enable it to be mounted under a sink or on a small table such as is indicated by the dotted lines in Figure 2. This is made possible by a unique arrangement for mounting of the various elements on the motor shaft including the elimination of outboard bearings on both sides of the cutting element, and also by the goose-neck feeding arrangement, each of which will be herein-after described in detail.

20 In the feeding arrangement shown in the drawings, there is a substantially vertical sheet metal duct 100 disposed above the motor and discharging into an elbow portion 101 having an inclined lower surface 102 down which the material may 25 slide when passing to the grinder. Duct 100 has a flange surrounding its top opening with apertures spaced around the flange to permit firm 30 securing to the top of a table, sink or other working surface indicated by the dotted line B. A swill block of rubber or similar material indicated by the dotted lines A may be placed over the inlet of the duct 100, said duct being slightly tapered downwardly in order that a flange on such block may be gripped by the side of the duct 35 when the former is inserted in the opening. This block which is conventional and forms no part of the present invention serves as a surface against which the edges of the dishes may be struck to loosen material resting on them, the 40 food or refuse falling through the block into the opening 100.

The lower end of the elbow member 101 is flanged and bolted onto the grinder housing 103 the end of which is apertured to retain an annular, flanged cover plate 104 rigidly secured thereto by bolts 105. The flanged portion 106 of the cover plate provides a surface exterior to the housing through which the bolts may be extended and the inner side of the end wall of the housing 45 are flush with the inner side of the cover plate. An annular groove is provided on this inner side of the cover plate for reception of a sealing ring on the cutter rotor, said groove being sufficiently deep to form not only an extended sealing surface 50 but also a radial bearing surface should the

rotor shaft deflect under load conditions. Normally, however, there is no bearing load on the cover plate but a close running fit is provided between its groove and the rotor to seal the opening against escape of material being ground. The central portion of the cover plate may be somewhat dished outwardly as at 107 to house the outer end of the rotor shaft, and a grease fitting 108 is provided in this dished portion, it being desirable that the space between the end of the rotor and the cover plate should be completely filled with grease.

The lower portion of a housing 103 is tapered into tubular form and leads downwardly at an angle from beneath the rotary cutter, the tubular end being threaded for securement to a pipe fitting through which the ground garbage is discharged. It will be seen from Figure 1 that the inlet to the grinder housing is disposed over the second quadrant of the rotor surface whereas the outlet is disposed so as to receive material approximately evenly from the entire lower half of the rotor. It will also be clear from reference to Figure 2 that the rotor housing has an inner surface defined by an inclined plate 109, the lower portion of which terminates in a horizontal edge parallel to the axis of the rotor at the margin between the second and third quadrants of the latter. The first quadrant of the rotor is totally enclosed by semicylindrical surface 110 in fairly close proximity to the periphery of the rotor. The underside, or third and fourth quadrants of the rotor, are enclosed by a semicylindrical grate 111, of hardened steel or other suitable material having a number of apertures closely spaced apart and with sharply defined edges to promote shearing action in cooperation with the rotor teeth. Grate or screen 111 rests in grooves formed in the end walls of housing 103 and is additionally supported at its mid point by a steel rib 112 extending longitudinally across the housing. With this construction when the edges on one side of the perforations in the screen 111 become worn, the screen may be turned around so that the rotor teeth may cut against the opposite edges of the perforations, thereby prolonging the useful life of the cutting surface.

From the foregoing it will be appreciated that the means for feeding garbage into the grinder comprises a plurality of passageways eventually feeding into the second quadrant of the rotor housing. As the rotor comes in contact with the screen 111 at the margin between the second and third quadrants a wedging action may take place which, due to the very high speed of the rotor (as high as 3600 R. P. M.) may cause material to be shot upwardly through the inlet passage. Such material is baffled by the surfaces defining the inlet passageway so instead of coming through the outlet 100, it is returned to the grinder.

The rotor cutter 113 comprises a plurality of discs 114 concentrically arranged about and journaled on a rotor shaft 115 which is an extension of the same rotor shaft of the electric motor furnishing the power. Each of the discs, with the exception of the two end discs 116, have teeth profiles formed in their outer peripheries, said profiles consisting of a radial cutting edge 117 approximately one-fourth the maximum radius of the discs and a rake portion gradually receding inward to the root of the next tooth. The curvature of this receding portion is approximately equal to the curvature of the screen basket 111 and affords a pocket of sufficient length and

depth to permit rapid grinding of the garbage. The peripheral cutting edges, which extend axially for the full width of the disc, are set only a few thousandths of an inch from the screen 111 so as to promote shearing action therebetween; a slight clearance however, is desirable for quietness of operation when the grinder is running empty.

The end discs 116 are of slightly larger diameter than the cutter discs, the diameters being such that they may afford a close running fit as previously described in the grooves formed in the end plates of the housing, the width of these discs 116 being approximately equal to the depth of said grooves, whereby the cutting discs disposed between the end discs may occupy the full length of the internal portion of the housing.

The entire cutter assembly including the end discs is retained together as a unit by a plurality of cap screws 118 with head portions countersunk flush with the end of the discs, the shank ends being threaded into the sealing disc at the opposite end of the assembly. The cutting discs are arranged so that the cutting teeth are staggered, preferably in herringbone fashion, with the cutting edges of the medially disposed discs behind the cutting edges of those discs nearer the ends of the rotor. This arrangement, which is best illustrated in Figure 3, promotes rapid movement of material into the grinder since there is a V-shaped pocket produced by the rake of the various teeth with the apex at the center of the rotor tending to drag material into the grinding case.

35 The rotor assembly 113 is not keyed to the rotor shaft 115 but is prevented from rotating with respect thereto by means of friction between a friction washer 119 retained by a lock washer 120 cooperating with a lock nut 121 the latter being threaded on the end of the rotor shaft 115. While the friction washer restrains the rotor from turning on its shaft during the normal grinding operation, should a piece of silver, or metal, manage to enter the grinder the impact of the rotor is cushioned by the possible slippage between the rotor and the shaft, and the shaft is protected from the sudden torque which would be developed if it were brought to rest immediately upon the locking of the cutter in its cage.

50 Rotor shaft 115 is supported by a pair of bearings 122 retained in races 123 supported by the motor frame 124. The mounting of the grinder housing on the motor frame is such that parts may be readily disassembled should the latter become necessary. This construction includes a flanged end bell 125 bolted or otherwise secured to the motor frame, said end bell having a face against which may be seated the inner end of the rotor housing, said parts being secured together by means of cap screws 126. Within the space behind the end sealing disc on the motor side are a plurality of countersunk apertures for receiving cap bolts 127 threaded into a bearing cap 128, the latter retaining bearing race 123. Bearing cap 128 is provided with a seal 129 enclosing the shaft at a point between the bearing and the motor. Labyrinth grease seals 130 are provided on the opposite side of the bearing between the shaft and the bell and directly behind the inner disc 116. Grease fitting 131 communicating with bearing 122 enables the space between the inner end of the rotor and the bearing to be packed with grease at frequent intervals. Shaft 115 is stepped down from the motor 70 to the rotor with a threaded portion engaged by

a lock nut 132 cooperating with a shoulder 133 on the shaft to retain the bearing race, a second shoulder 134 forming a seat preventing end displacement of the grinding rotor assembly.

Figure 2 illustrates how the rotor shaft 115 is extended through the motor on the opposite side from the rotor cutter, there being a similar bearing and seal construction to that described in the preceding paragraph. The end of the shaft 135 in this instance however extends beyond the housing and is provided with such an exterior configuration that it may be gripped by a hand crank 136 (shown in Figure 4) and the rotor held against turning during the removal of the lock nut 121 at the opposite end should it be desired to remove the rotor. Conversely the hand crank may be used to manually turn the rotor should it be desirable to do so. End portion 135 is enclosed by a hub cap 137 which can be readily removed when hand crank 136 is to be employed.

To assist in the grinding operation and to flush material through the perforated cage 111 a source of water is connected with a spray pipe 138 which extends horizontally at the junction between the inclined portion 102 of the feed passageway and inlet duct 100. This spray pipe has a series of perforations extending longitudinally thereof which direct water down the inclined surface 102 and assists in charging the material uniformly into the grinder. Flushing water should be flowing through the grinder before material is fed into it and with a grinder adapted to handle approximately four hundred pounds of garbage per hour, approximately four gallons of water per minute should be employed. Excess water tends to flood the grinding compartment and increases the power consumption.

As previously stated, the feeding apparatus is such that it will prevent garbage from being thrown back by the rotary cutter and is also of such length and contour as to make it difficult for an operator to reach down through the feed inlet and touch the cutter while it is in operation. Such garbage as is thrown upwardly by the rotor is confined by the upper surface 139 of the elbow shaped feed inlet. Further baffling is produced by a deflecting partition 140 forming an extension of one side of the feed inlet and separating the feed inlet and the elbow portion 101. It should be observed that the elbow shaped feed inlet is arranged parallel to the axis of the rotor and feeds into that side of the rotor where the rotor is moving away from the feed duct.

Should the machine stall due to an overloading of material, it is possible through the use of the hand crank 136 to rock the rotor back and forth while the unground garbage is being removed. The bolted connection between the feed portion 101 and the housing proper, 103, permits ready access to the cutting compartment to facilitate removing material in such instances.

Should one want to disassemble the unit, the operator first removes the bolts retaining the flanged cover plate. At this stage it is possible to slide the cutting screen directly out from beneath the rotor so that it may be cleaned if need be, or turned end for end to present the unused cutting edges of the perforations as a cutting surface should the opposite edges have become dulled through use. Should it be desirable to remove the rotor the hand crank 136 is employed to prevent the rotor shaft from turning and the lock washer 120 and friction gasket 121 are removed and the entire rotor assembly 113 is slid off the shaft. The design of the rotor cutting

teeth is such that they may be reground radially without grinding the arc of the tooth, the same rake being maintained at all times. Due to the slight rake which is employed, this cutting edge 5 may be reground several times without appreciably diminishing the clearance between the edge of the teeth and the grinding cage 111. Should this clearance become too great however, the cage 10 may be easily shimmed up to provide close clearance.

Should it be necessary to replace or repair the front motor bearing, the same operations are performed, including the removal of the rotor assembly, thereby making accessible the cap bolts 15 127 which secure the end bell 125 to the bearing cap 128. Removal of cap bolts 127, cap screws 126 and also the nuts which fasten the flange end bell to the motor permits removal of the entire 20 housing, the flanged end bell and the oil seals 129, thereby exposing the front motor bearing for repair or replacement. To reassemble the unit these operations are performed in reverse order.

Despite the high speed of the rotor, the pockets formed ahead of the cutting edges are sufficiently long and deep to permit material to enter the space between the cutting edges of the rotor 25 and the grinding cage. With the rotor operating at a speed of 3500 R. P. M., a three tooth cutter of only five inch diameter shaped in the precise 30 manner described and illustrated herein can handle upwards of four hundred pounds of garbage per hour, and one and one-half horsepower motor is sufficiently powerful to handle the material at this rate. While the invention is not limited to precise details of construction, the foregoing detailed illustration of an embodiment of the invention will illustrate the practice thereof.

The invention having been described, what is claimed is:

- 40 1. In a grinding machine, a rotor shaft and a grinding element journalled on said shaft, a grinding housing enclosing said grinding element and having a grinding surface cooperating with said grinding element to produce grinding action, 45 bearings supporting said shaft at one side of said grinding element only, frictional means cooperating with said shaft and grinding element providing yieldable connection therebetween, and a cover plate secured to said housing enclosing the 50 unsupported end of said shaft, said cover plate having an axially disposed surface sealing said grinding element and arranged to provide bearing support should the shaft deflect under grinding loads.
- 55 2. In a grinding machine, a rotor shaft, and a grinding element journalled on said shaft, said element composed of disc members assembled and locked as a unit, a housing enclosing said grinding element and having a grinding surface cooperating with said grinding element to produce grinding action, 60 bearings supporting said shaft in an overhanging manner, friction means cooperating with said shaft and grinding element causing them to rotate together, and a cover plate secured to said housing enclosing the unsupported end of said shaft, said cover plate having an axially disposed surface sealing said grinding element and arranged to provide bearing support for the shaft through the friction means should the shaft deflect under grinding loads.
- 65 3. In a rotary grinder, a rotor shaft, an enclosing grinding housing, a grinding surface in said housing, a unitary rotary grinding element journalled on said shaft, arranged to provide 70

grinding action with said surface, said element including individual plates locked together and having cutting edges on their peripheries, bearings supporting said shaft in overhanging relationship, frictional means cooperating with said shaft and grinding element providing yieldable connection therebetween, and a cover plate secured to said housing enclosing the unsupported end of said shaft, said cover plate having an axially disposed surface sealing said grinding element and arranged to provide bearing support should the shaft deflect under grinding loads.
